UNITED STATES PATENT OFFICE.

JAMES M. McCLELLON, OF EVERETT, MASSACHUSETTS.

CONDENSER FOR LOCOMOTIVES.

1,093,942.

Specification of Letters Patent. Patented Apr. 21, 1914.

Application filed February 14, 1908. Serial No. 415,826.

To all whom it may concern:

Be it known that I, JAMES M. McCLELLON, a citizen of the United States, residing at Everett, county of Middlesex, and State of Massachusetts, have invented an Improvement in Condensers for Locomotives, of which the following description, in connection with the accompanying drawing, is a specification, like letters on the drawing representing like parts.

This invention has for its object the production of a novel condenser which is especially designed for use in connection with locomotive boilers. The condenser is of that type which is situated at the front end of the locomotive in such position that as the locomotive is traveling air currents will be forced over the condensing surfaces thereby to condense the steam therein.

My improvement relates to a novel construction of condenser whereby the air currents which pass through the condenser are utilized to the best advantage in cooling the condensing surfaces, and whereby the air which passes through the condenser and becomes heated can be delivered to the fire box for promoting combustion. My improved condenser is also so arranged that any steam which is not condensed therein can freely escape to the atmosphere.

The advantage of this construction is that there is no back pressure on the cylinders other than atmospheric pressure and the full pressure of the steam thereon is employed in doing useful work.

In the drawings I have shown some embodiments of my invention without however attempting to illustrate all ways in which the invention may be made.

Figure 1 is a vertical section through the front end of the locomotive boiler having my improvements applied thereto; Fig. 2 is an enlarged section on the line $x-x$, Fig. 1; Fig. 3 is an enlarged section on the line $y-y$, Fig. 1; Fig. 4 is a section through the smoke stack on the line $a-a$, Fig. 1; Fig. 5 shows a different form of smoke stack from that shown in Fig. 1; Fig. 6 illustrates a still different form of smoke-stack; Fig. 7 is a detail showing the manner of securing the cap on the smoke stack.

My invention can be used with any of the familiar types of locomotive boilers and I

have in the drawings shown only a sufficient portion of the locomotive to enable the invention to be properly understood.

3 is the front portion of the shell of an ordinary tubular locomotive boiler, and 4 the flues which lead from the fire-box through said shell and into the usual smoke chamber 5, said flues being secured to the flue-sheet 6.

7 are the steam pipes which lead the steam from the steam dome to the engine cylinders 8. These parts are such as are commonly found in locomotive boilers and form no part of my present invention.

According to my invention I arrange a condenser in front of the shell 3 and provide said condenser with condensing surfaces in the form of pipes or tubes through which the exhaust steam passes, and I also arrange said condenser so that as the locomotive is in motion currents of air are forced over said condensing surfaces thereby cooling them and condensing the steam.

In the preferable embodiment of my invention the condenser is cylindrical in cross sectional shape and has a diameter substantially equal to that of the shell, so that the application of my condenser to a locomotive does not increase its height or its width but merely increases its length.

In the embodiment of the invention herein illustrated the condenser is confined within a shell 9 which extends forwardly from the smoke chamber 5. Said shell 9 is divided from the smoke chamber by a partition or sheet 10. Situated within the condenser are two separate steam chambers 13 and 130 with which communicate the headers 17, 19, 18 and 20, the headers 17 and 19 communicating with the upper steam chamber 13 and the headers 18, 20 communicating with the lower steam chamber 130. The steam chamber 13 communicates through a connection 14 with the exhaust passage 12 into which the steam is exhausted from the engine cylinders. The pair of headers 17 and 18 are connected all along their length by two sets of pipes 15 and the pair of headers 19 and 20 are similarly connected by two sets of pipes 16, said pipes 15, 16 forming the condensing surfaces.

The headers 17, 18, 19, 20 are preferably inclined somewhat, the headers of each pair

being nearer together at their rear ends than at their front ends. The pipes 15, 16 are arranged along the full length of the headers. Associated with the pipes are deflectors 5 which are arranged to deflect the currents of air against the pipes and which close up any passageways between the pipes through which the air might pass without coming in contact with said pipes. One of these deflectors is shown at 21, and it is circular in cross sectional shape and is secured at its front end to the outer sides of the headers 19, 20, and at its rear end to the inner sides of the headers 17, 18. Another deflector 22 10 is situated between the headers 19 and 20 at their rear end, said deflector being substantially conical in shape. The deflector 21 encircles all the pipes 16 and the headers 19 and 20, but is situated within all the 15 pipes 15, while the deflector 22 is situated entirely within the pipes 16.

The front ends of the headers 17, 18 are situated closely adjacent to the shell 9 and the pipes 15 at the front ends of the headers 25 are also closely adjacent to said shell. With such a construction there is an annular passageway 26 formed between the shell 9 and the deflector 21, in which passageway all the pipes 15 are arranged, and another annular passageway 27 formed between the two deflectors 21 and 22, in which latter passageway all the pipes 16 are arranged. Furthermore, the pipes 15 and 16 are arranged in rows extending diagonally across the passageways so that no currents of air can pass 30 through either passageway without impinging on the pipes therein.

The casing 9 is formed with a discharge opening 23 in its lower side which leads into 40 a chamber 24 that communicates with a discharge conduit 25 which may if desired extend back to the fire-box of the locomotive. The steam which is exhausted from the locomotive passes from the exhaust passage 12 into the connection 14 and thence into the steam chamber 13 and into the headers 17 and 19 from which it circulates through the pipes 15 and 16 into the headers 18 and 20 and into the steam space 130.

50 When the locomotive is in motion, currents of air will be forced through the passageways 26 and 27 and discharged through the outlet 23 and in its movement through said annular passageways it contacts with 55 the condensing pipes 15, 16 and thus condenses the steam therein. Any water of condensation accumulating in the headers 17, 19 will be discharged through the pipes 15, 16 into the lower headers 20 and 18. 60 Any water of condensation accumulating in the header 20 will be discharged through a connection 28 into the lower header 18, and the water accumulating in said lower header 18 will be discharged through a pipe 29 65 which connects with said header and which

will preferably lead back to the boiler or to a reservoir from which it is delivered to the boiler in usual manner, so that the water may be used over again. Any water of condensation accumulating in the space 70 130 will be led back to the boiler through a pipe 60.

In the preferred embodiment of my invention the condenser is open to the atmosphere so that any steam which is not condensed in 75 the condenser may freely escape. By means of this construction the back pressure on the pistons will never exceed atmospheric pressure and the full pressure developed in the boiler will be expended in doing useful work. 80

In the embodiment of the invention herein shown the steam space 130 has communicating therewith one or more pipes 37 which lead into a continuously-open exhaust duct 32 through which any steam which is not 85 condensed may freely escape into the smoke chamber.

I have shown a fan 30 in the discharge conduit 25 which may be used for regulating the air currents over the condensing pipes. 90 If the engine is at rest, or if it is moving so slowly that the speed of the engine will not produce sufficient air currents for condensing the steam, the fan may be set in operation to assist in producing the necessary air 95 currents over the condensing pipes. Similarly, if the engine is moving rapidly, the fan may be used to retard the flow of the air through the conduit 25 and thus regulate the amount of condensation. It will 100 be understood that the conduit 25 may discharge the air delivered thereto at any point. If, however, the conduit leads back to the ash pan of the locomotive, the fan 30 may be useful in forcing air into the fire-box. This 105 fan may be operated in any suitable way as by means of a steam turbine 31 which is under the control of the engineer in the cab. I have also provided a construction wherein the steam may be exhausted directly into the 110 smoke chamber through the nozzle 32 as is commonly done in locomotives, if for any reason it is not desired to use the condenser. To accomplish this, I have provided the valve 33 which controls communication between the exhaust passage 12 and either the connection 14 or the nozzle 32, said valve in one position closing communication between 115 said exhaust passage 12 and the nozzle 32, as shown in Fig. 1, and directing the steam 120 into the steam chamber 13, and in another position closing communication between the exhaust passage 12 and the steam chamber 13 and directing steam into the exhaust nozzle 32. The valve 33 is shown as attached to 125 a rock shaft 41 which extends out through the side of the locomotive and which may be operated from the cab by any suitable connection (not shown).

It is desirable that there should be a cer- 130

tain amount of suction created in the smoke chamber 5 because otherwise the pressure of the air delivered into the closed ash-pan of the fire-box through the conduit 25 will 5 produce sufficient pressure in the combustion chamber so that when the doors are open for stoking the fire or shoveling in coal the hot gases will escape through the door. Accordingly I have provided a device which is 10 designed to maintain in the smoke chamber sufficient suction to provide the necessary draft through the flues 4. To prevent an excess of pressure in the combustion chamber I have herein shown two devices for this 15 purpose either or both of which may be used.

In Fig. 1 the smoke stack is designed in such a way that as the locomotive is traveling rapidly the currents of air passing through the smoke stack will produce the 20 necessary suction in the smoke chamber. This necessary suction may also be produced by mechanical means such as a fan.

Referring first to the smoke stack feature, the arrangement shown in Fig. 1 comprises 25 a main stack 40 which communicates with the smoke chamber and which is provided with an outlet opening 42 in its side. This smoke stack is surrounded by a hood 43 which is of a general cylindrical shape open 30 at its ends. The smoke stack 40 is also preferably provided with the cone-shaped projection 44 which extends into the front end of the hood 43. The hood is larger than the smoke stack so that there is a passageway 35 45 provided at each side of the smoke stack. With such a construction it will be seen that as the locomotive is moving rapidly the air which passes through the hood and through the passages 45 will create more or 40 less suction at the outlet 42 of the smoke stack, the amount of suction depending upon the speed at which the locomotive is moving. This suction at the outlet 42 will produce the necessary suction in the smoke chamber to 45 establish a good draft through the flues.

The upper end of the smoke stack is normally covered by a cap 46 which may be removed if it is desired to exhaust the steam directly into the nozzle 32 in the usual way 50 instead of exhausting the steam into the condenser. This cap 46 is secured to the smoke stack by means of a bayonet joint 47, shown best in Fig. 7.

In Fig. 5 I have shown a different form of 55 the device wherein the smoke stack 400 leads into a hood or suction-producing device 430. The smoke stack 400 is bent rearwardly slightly at its upper end and the suction device 430 has the horizontally-arranged inlet 60 end 49 and the upwardly-directed exhaust end 50. The hood is larger than the smoke stack so that the air which enters the front end thereof can freely pass around said smoke stack, and in passing through the 65 suction device the requisite suction is pro-

duced in the smoke chamber. In this form of the invention the smoke stack is continuously open.

In Fig. 6 a different form of the device is illustrated wherein the smoke stack 401 is 70 bent rearwardly at its upper end and leads into a suction-producing device or nozzle 51 which is larger than the smoke stack, said nozzle 51 having the flaring inlet end 52. The smoke stack 401 also carries a suction- 75 producing device 53 which is in the form of a nozzle having a flaring opening and in which is situated a cone-shaped member 54 arranged to present an annular passageway through the member 53. In this construc- 80 tion also the smoke stack is constantly open and the motion of the locomotive will produce the required suction in the smoke chamber. In addition to these features I may provide a mechanical means, such as a fan 85 34, for producing the necessary suction in the smoke chamber. This fan is shown as arranged within a housing 81 and is designed to force air through said housing into the passageway 35 and thence into the 90 exhaust nozzle 32. Said fan may be operated in any suitable way and is herein shown as being geared to the turbine 81 by means of gearing 36. When rotated rapidly this 95 fan will force sufficient air through the nozzle 32 to provide the necessary suction in the smoke chamber.

In Fig. 1 the casing 81 is shown as being closed by a cap 82. When it is desired to force air through the casing by the fan, said 100 cap is removed by sliding it to the left on the shaft 83 of the fan. For this purpose the cap will preferably have connected thereto suitable mechanism by which it may be operated from the cab. When the cap is in place, 105 the fan will be operated to force air through the passageway 35, as will be obvious.

The device as shown in Fig. 1 is so arranged that the condenser may be made use of or the steam may be exhausted directly 110 into the smoke chamber in the usual way as desired.

Where the necessary draft through the fire-box is secured in the usual way by exhausting the steam directly into the smoke 115 chamber the suction produced is often sufficient to draw through the flues small particles of coke and unburned coal which either accumulate in the smoke chamber or are exhausted through the smoke stack and are thus wasted. Many of these small particles are exhausted while still red hot and are liable to cause fires along the line of the railway. One advantage of my construction is that a sufficient draft can be produced 120 without any danger of sucking such particles of hot coke and coal through the flues and thus all the waste and danger occasioned by the throwing out of sparks by the locomotive 125 is avoided.

Other advantages of the device herein shown are that the air which is used in combustion is heated and thus a saving is effected; the water which results from the condensation of the steam is delivered to the boiler in a heated condition and thus still further saving is effected; since the water is used over and over again the accumulation of scale in the boiler is materially decreased 10 because the condensed water is delivered to the boiler in a comparatively pure state; and all back pressure above atmospheric pressure is removed from the pistons because of the fact that the steam is exhausted 15 directly into the condenser under no pressure.

I do not herein claim the manner of securing a suction in the smoke chamber without the aid of the exhaust steam.

20 Having fully described my invention, what I claim as new and desire to secure by Letters Patent is:—

1. The combination with a locomotive boiler, of an open-ended casing extending 25 forwardly beyond the smoke chamber, condensing pipes within said casing, means to admit the exhaust steam into said pipes and means within the casing to deflect air currents across said pipes.

30 2. The combination with a locomotive boiler, of a condenser situated in front thereof, said condenser comprising a plurality of pipes through which the steam is exhausted, and deflectors within the casing to deflect air 35 currents against said pipes.

3. The combination with a locomotive boiler, of a condenser comprising an open-ended casing extending forwardly from said boiler, concentrically-arranged condensing 40 pipes within said casing, means to admit the exhaust steam to said pipes, and deflectors to deflect air currents across said pipes.

4. The combination with a locomotive boiler, of an open-ended casing extending 45 forwardly therefrom, a plurality of sets of concentrically-arranged condensing pipes within said casing, means to admit the exhaust steam to said pipes, and means to deflect air currents across said pipes.

50 5. The combination with a locomotive boiler, of an open-ended casing extending forwardly therefrom, two upper headers and two lower headers extending longitudinally

of the casing, pipes connecting said upper and lower headers, and means to admit the 55 exhaust steam to said pipes.

6. The combination with a locomotive boiler, of an open-ended circular casing extending forwardly from the boiler, annular deflectors within said casing forming annular 60 passageways, and condensing pipes located within said passageways.

7. The combination with a locomotive boiler, of an open-ended casing extending forwardly therefrom, annular deflectors 65 within the casing forming annular passageways therein, a pair of headers in each passageway, and condensing pipes connecting the headers of each pair.

8. The combination with a locomotive 70 boiler, of an open-ended casing extending forwardly therefrom, annular deflectors within the casing forming annular passageways therein, a pair of headers in each passageway, condensing pipes connecting the 75 headers of each pair, and a return pipe communicating with the lower headers of each pair for returning the water of condensation to the boiler.

9. The combination with a locomotive 80 boiler, of an open-ended casing extending forwardly therefrom, two steam chambers within said casing, one of which is connected to the exhaust passage leading from the cylinders, a pair of headers communicating 85 with each steam chamber, and condensing pipes connecting each header of one pair to a header of the other pair.

10. The combination with a locomotive boiler having a smoke chamber and an exhaust nozzle, of an open-ended casing extending forwardly from the smoke chamber, two steam chambers within said casing, condenser pipes connecting said chambers, means to deliver the exhaust steam to one 90 chamber, a pipe connecting the other chamber with the exhaust nozzle, and means to collect and return to the boiler the water of condensation.

In testimony whereof, I have signed my 100 name to this specification, in the presence of two subscribing witnesses.

J. M. McCLELLON.
